UNITED STATES PATENT OFFICE

146,608

DESIGN FOR A DRILL PRESS

John McLeod Little, Toledo, Ohio, assignor to
Defiance Machine Works, Inc., Defiance, Ohio,
a corporation of Ohio

Application October 31, 1945, Serial No. 123,375

Term of patent 14 years

(Cl. D63—1)

To all whom it may concern:

Be it known that I, John McLeod Little, a citizen of the United States, residing at Toledo, in the county of Lucas and State of Ohio, have invented a new, original, and ornamental Design for a Drill Press, of which the following is a specification, reference being had to the accompanying drawings, forming a part thereof.

In the drawings:

Fig. I is a perspective view showing the front and one side of the drill press embodying my new design;

Fig. II is a perspective view showing the front and the other side of the drill press of my design; and

Fig. III is a perspective view showing the rear side of the drill press of my design.

I claim:

The ornamental design for a drill press, as shown.

JOHN McLEOD LITTLE.
